United States Patent Office.

JOHN C. BRYANT AND ANDREW W. TURNER, OF GARDNER, MASSACHUSETTS.

Letters Patent No. 97,350, dated November 30, 1869.

IMPROVEMENT IN MACHINE FOR TURNING WOODEN WARE.

The Schedule referred to in these Letters Patent and making part of the same.

To all whom it may concern:

Be it known that we, JOHN C. BRYANT and ANDREW W. TURNER, of Gardner, in the county of Worcester, and State of Massachusetts, have invented a new and useful Improvement in Machine for Turning Wooden Ware; and we do hereby declare that the following is a full, clear, and exact description thereof, which will enable others skilled in the art to make and use the same, reference being had to the accompanying drawing, forming part of this specification.

This invention relates to a new and useful machine for turning and squaring the ends of wooden pails, tubs, kegs, and other wooden ware, and consists of a frame or foundation with sliding transverse bars, bearing knives or cutters, and operated by levers, as hereinafter more fully described.

In the accompanying drawing—

Figure 1 represents a top view, showing the arrangement of the cutters and the levers.

Figure 2 represents a front view.

Similar letters of reference indicate corresponding parts.

A is the foundation-plate.

B B represent the cutters, which are attached to slides C C', which are confined in dovetail grooves on each end of the foundation, so that they may slide transversely across it, as seen in the drawing.

A pail is represented in red color, and it will be seen that the foundation A, with the parts attached thereto, is placed inside the pail, this squaring and turning of the ends being done before the bottom is put in, the pail being placed in a "chuck" for the purpose.

To properly adjust the cutters to the ends of the pail, the foundation is confined by a central pivot, the orifice of which is seen at D.

The cutters are moved up to the pail by means of the lever E, which has its fulcrum at F, the short end being connected with the slide C at g.

The long end extends outside the pail, with a handle upon it, as seen at h.

I is another lever, which is actuated by the lever E, they being connected together, as seen at J.

The fulcrum of the lever L is at k, and it is connected to the slide C' at L.

m is a stationary guide.

The slides C C' bear the cutters which square and round the edges of the pail.

It will be seen that this may all be done at one operation, thus greatly facilitating the work, and performing it much more perfectly than by the ordinary process.

Having thus described our invention,

What we claim as new, and desire to secure by Letters Patent, is—

In combination with the foundation A, the slides C C', bearing the cutters B, the guide m, and the levers E and I, arranged and operating substantially as described, for the purposes set forth.

JOHN C. BRYANT.
ANDREW W. TURNER.
